UNITED STATES PATENT OFFICE.

CORNELIUS G. HASTINGS, OF WEST HOBOKEN, NEW JERSEY.

TUNNEL CONSTRUCTION.

1,256,312.

Specification of Letters Patent. Patented Feb. 12, 1918.

Application filed July 2, 1913. Serial No. 776,898.

To all whom it may concern:

Be it known that I, CORMELIUS G. HASTINGS, a citizen of the United States, and a resident of the city of West Hoboken, county 5 of Hudson, and State of New Jersey, have invented certain new and useful Improvements in Tunnel Constructions; and I do hereby declare that the following is a full, clear, and exact description of the same, reference being had to the accompanying drawings, and to the numerals of reference marked thereon, which form a part of this specification.

This invention relates to means for rapidly and efficiently lining a tunnel during the projection of the bore. Heretofore various means have been in use for constructing the walls or lining of a tunnel, which involve a great deal of labor and time, but by 20 my invention the walls or lining of the tunnel may be erected in true geometrical form in a quick and ready manner.

It is an object of this invention to provide interfitting sectional blocks which may be readily assembled on supports to form the walls of the tunnel and from which the supports may then be removed.

It is also an object of this invention to provide a plurality of interfitting concrete 30 block sections and means integrally associated therewith to facilitate rapid assembly thereof upon the forms.

It is also an object of this invention to provide interfitting reinforced concrete block 35 sections adapted to be built one upon another in arched relation, and means for rigidly connecting the adjacent sectional block arches or rings.

It is also an object of this invention to provide a sectional form upon which the block sections may be rigidly engaged during assembly thereof and whereby said forms may be easily removed from the assembled block sections.

It is finally an object of this invention to afford a sectional tunnel construction whereby the respective sections are provided with integral means for facilitating rapid assembly and permanent alinement of the same.

The invention (in a preferred form) is

illustrated in the drawings, and hereinafter more fully described.

In the drawings:

Figure 1 is a transverse section through a tunnel under construction, showing the sectional wall blocks embodying part of my invention in elevation and in section.

Fig. 2 is an enlarged section taken on line 2-2 of Fig. 1.

Fig. 3 is a modification showing double track tunnel sections of elliptical contour.

Fig. 4 is a diagrammatic section showing the relation and connection existing between adjacent forms.

Fig. 5 is a detail elevation illustrating the splice bar connection between adjoining sections of the form.

Fig. 6 is a detail of a concrete block sectioned at different portions to disclose the reinforcing members.

Fig. 7 is an inner radial view of a reinforcing skeleton for a sectional block.

Fig. 8 is a side elevation of a part of a tunnel wall under the course of construction and shown partly in section and partly in elevation.

Fig. 9 is a similar enlarged fragmentary view thereof.

Fig. 10 is a fragmentary section similar to Fig. 2 and illustrating a modified form of block and the means of connection between adjacent ones.

Fig. 11 is a perspective detail of a channel member forming a part of each block.

As shown in the drawings:

The concrete blocks or voussoirs are indicated by the reference numerals 1, and 2. Each block comprises an annular segment composed of concrete formed about a suitable reinforcing frame. Such a frame comprises corner angle bars 3, to which are suitably attached by brazing or otherwise, the metallic reinforcing bars 4, and 5, respectively. A strip of foraminous material 6, such as wire mesh, extends around the wall 90 of the block beneath the surface and is connected with the reinforcing frame, thus affording a large and efficient bonding surface for the concrete.

A channel member 7, conforming to the 100

curvature of the inner surface of the sectional blocks is embedded therein and the flanges thereof are stamped outwardly as indicated by the reference characters 7^a 5 affording apertures at points near the webbing of said members, to receive the anchors 8, therein. As shown, said anchor elements comprise a relatively short bar of metal with one end turned at an angle of approximately 10 ninety degrees and the other end apertured to receive the attaching bolts 9, therein. The form upon which the concrete block sections are assembled consists of a plurality of curved I-beam sections 10, the extremities of 15 which are angled to permit ready taking down of the same by withdrawing said sections inwardly. When in assembled relation, said sections are connected together by means of splice bars 11, which are apertured correspondingly with the I-beam sections to receive the clamping bolts 12, therethrough. Each of said I-beam sections is apertured at points corresponding with the apertures in the channel members 7, of the block sections, 20 thereby adapting the anchors 8, to be attached to the I-beam sections by means of the bolts 9, and when said bolts are drawn tight, engaging in said apertures in the channel 7, and in recesses alined therewith in the concrete proper of the block sections. A twisted bar 13, known as a spacer, having the ends thereof bent parallel one another, may be removably connected to adjacent forms by means of removable bolts 14, engaged in 25 suitable apertures in the I-beam sections.

Means are provided for maintaining and insuring the correct alinement of the adjacent block sections. This consists of a number of sections of piping 15, engaged 30 for approximately half their respective lengths in apertures in the block sections, with a portion of each extending and projecting outwardly from one side of the block section. Inasmuch as said block sections 1, and 2, are similarly constructed, a complementary recess is afforded on one side to receive the projecting end of the pipe 15, of an adjacent section therein, so that as assembled a continuous pipe lined 35 aperture extends through the tunnel wall. Rods 16, which may suitably be of a length equal to the width of the block sections are inserted in said pipes 15 so that substantially half the length of each of said rods 40 extends into the adjacent block section, thereby affording a stiffening and alinement element at the abutting ends of the pipes 15, and also affording means facilitating the rapid and accurate positioning of 45 the respective sections relative one another.

In the modification illustrated in Fig. 10, the blocks are shown as built upon a frame which is provided instead of the corner angle irons 3, with the Z-bars 19, thus leav-

ing a peripheral channel in the outer surface of the tunnel wall at the intersection of adjacent blocks. Sheathing elements 20, may be used in connection with the blocks, either bolted together around the outer surface of a block after the same has been inserted in position, or rigidly attached to the block when the same is constructed. 65 70

It is to be noted that the corner edges of the blocks are recessed to afford a radially directed aperture 21, in the wall of the 75 tunnel which together with the channels afforded between adjacent blocks in the Z-bar construction may be filled with grouting to insure a sealing of the wall at the abutting faces of the blocks. 80

The operation is as follows:

The tunnel lining or wall herein described may be advantageously used with a tunnel shield by which the bore is projected forwardly, and, when such is the 85 case, as for instance when the shield has been advanced a certain amount due to the extension of the projecting means, the projecting means are unseated from the end of the completed tunnel lining and another 90 ring of block sections placed in position.

The forms 10, afford a means for building the block sections one upon another in correct geometrical form, the anchors 8, serving to maintain the sections in position until the wall has set. For the purpose of alining the respective block section rings or arches, the pipes 15, and rods 16, affording a continuous and interfitting system of dowels, are used. Thus in the projecting 100 end of one of the pipe sections 15, the rod 16, is inserted, which, due to the fact that the rod lengths and pipe lengths abut one another in staggered relation, projects outwardly beyond the projecting end of the 105 pipe, thereby affording an alining means for placing the next adjacent block section into position upon its respective ring form.

When the block sections of the tunnel lining have been assembled and a key block 110 17, inserted, the anchor bolts 9, are removed, thereby permitting withdrawal of the anchors 8, to free the respective form sections from the block sections. Likewise the bolts 14, are removed to permit the detachment 115 of the spacers 13, thus disconnecting adjacent ring forms. The bolts 12, securing the splice bars are removed and, due to the angularity of the ends of the form sections, the same may be drawn inwardly, thereby 120 disassembling the form. If desired the ring forms and anchor bolts may be left in the built up block rings and the whole covered with concrete as shown also in Fig. 2. After the removal of the form the channel members and apertures in the block sections are 125 filled in with concrete, denoted by the reference numeral 18, as shown in Fig. 2.

Fig. 8, is a clear representation of the process of construction of the tunnel lining. At the right is seen a pair of forms spaced and held in proper position by the spacers 5 13, still secured in the adjacent and last constructed block sectional ring. As the work progresses the forms are removed from those rings which have taken the required set and the spaces existing on the inner surfaces 10 thereof filled with concrete to afford a smooth facing as the inner surface of the tunnel.

Fig. 1, shows a tunnel construction for a single track subway whereas Fig. 3, illustrates a construction adapted for a double track thoroughfare. However, the method of construction is the same in each case.

I am aware that details of construction may be varied through a wide range. Any 20 desired geometrical section may be constructed, but for convenience of illustration I have described a tunnel of circular cross section. Other various details relating to the form and adaptation of the reinforcing 25 elements and the forms or alining means may be varied through a wide range without departing from the spirit of this invention. I therefore do not purpose limiting the patent granted otherwise than necessi- 30 tated by the prior art.

I claim as my invention:

1. A tunnel lining comprising a plurality of complementary block sections, reinforcing members embedded therein, sectional 35 forms for arranging the sections in proper geometrical relation, clamps secured to the form sections engaging the block sections for rigidly securing the forms in place and means connecting the adjacent forms for 40 connecting the adjacent block sections together.

2. In a tunnel lining a plurality of sectional complementary blocks, forming means for building the same in proper geometrical 45 form, means integrally associated with each of said blocks permitting clamping engagement with said forming means to hold said blocks in position, space bars connecting adjacent forming means to reinforce and aline 50 the same, and means permitting the removal of the forming means when the respective wall portions of the tunnel have set.

3. A tunnel lining comprising a plurality of sectional complementary concrete blocks, 55 a plurality of apertures extending transversely therethrough, pipe sections inserted in apertures in adjacent block sections to connect and aline the same, rods inserted in said pipe sections to facilitate such operation and reinforce the connection between adjacent blocks, and collapsible forms upon which said blocks may be assembled in proper geometrical form.

4. A tunnel lining comprising a plurality

of block sections having channels therein, 65 means for securing the sections together in alinement and collapsible curved sectional forms adapted to engage in said channels and to hold the blocks in proper assembled relation. 70

5. A tunnel construction comprising a collapsible form, a plurality of block sections, means securing adjacent forms rigidly together to insure proper positioning of the block sections thereon, and continuous sectional members extending longitudinally of the tunnel lining and through said block sections to reinforce and maintain the same 75 in proper relation.

6. In a device of the class described the 80 combination with a knockdown form, of blocks grooved to interfit therewith and having notches therein, said form adapted to be set up to permit a number of blocks to be held in position thereby to form the 85 walls of a tunnel, and clamps adapted to be rigidly engaged to said forms and engage in said notches to hold the forms in place.

7. In a tunnel construction, reinforced concrete block sections, an apertured channel member embedded therein, and collapsible forms adapted to be releasably anchored in said channel members to hold the respective blocks in proper position. 90

8. A tunnel construction embracing complementary concrete block sections, form sections for supporting the blocks and a plurality of clamps removably secured to each form section for clamping the respective blocks and sections in rigid relation. 95

9. A tunnel construction embracing complementary concrete block sections, form sections for supporting the blocks, a plurality of clamps removably secured to each form section for clamping the respective blocks 105 and sections in rigid relation, spacing bars for spacing the forms the proper distance apart and tie bars for rigidly connecting the form sections.

10. A tunnel construction embracing complementary block sections provided with apertures therethrough, interfitting sectional members adapted to be inserted in said apertures to aline the blocks, a form section for each block, members for clamping the 115 block and form section together and means for rigidly connecting adjacent form sections. 110

11. In a device of the class described sectional forms, block sections adapted to interfit therewith, means for clamping the forms directly to the respective block sections and means for connecting the form sections longitudinally and transversely to form a rigid structure. 120

12. In a device of the class described sectional forms, block sections adapted to interfit therewith, means for clamping the

4
forms directly to the respective block sections, means for connecting the form sections longitudinally and transversely to form a rigid structure, and members extending through the block sections for aligning the same.

5 In testimony whereof I have hereunto

subscribed my name in the presence of two subscribing witnesses.
